Shurdon & Bates.

UNITED STATES PATENT OFFICE.

EDWARD M. BARNES, OF CLEVELAND, OHIO.

MAGNETIC BRAKE.

SPECIFICATION forming part of Letters Patent No. 650,628, dated May 29, 1900.

Application filed August 16, 1899. Serial No. 727,365. (No model.)

To all whom it may concern:

Be it known that I, EDWARD M. BARNES, a citizen of the United States, residing at Cleveland, in the county of Cuyahoga and State 5 of Ohio, have invented a certain new and useful Improvement in Magnetic Brakes, of which the following is a full, clear, and exact description, reference being had to the accompanying drawings.

10 The object of my invention is to provide a simple and efficient track-brake for railway cars. I accomplish this by suspending a magnetic brake-shoe on the truck of the car over the track, with provision for such movement 15 that when electric current is thrown through the shoe it will move into engagement with the track and retard the car, the track constituting the armature of the magnets.

The invention consists of the means herein- 20 after shown, described, and claimed by which I make a very simple and satisfactory brake-shoe and efficiently support it.

The drawings clearly show my invention as applied to an ordinary truck of a street-car.

25 Figure 1 is a side elevation of the truck. Fig. 2 is a plan, partly broken away, of the brake-shoe and its supporting parts. Fig. 3 is a vertical section on the line 3 3 of Fig. 2. Fig. 4 is a side elevation, partly sectional and 30 partly broken away, of the brake-shoe and its supporting parts. Fig. 5 is a horizontal section on the line 5 5 of Fig. 4. Fig. 6 is a dia- 35 gram illustrating the winding of the shoe, and Fig. 7 is a horizontal section on the line 7 7 of Fig. 3.

Referring to the parts by letters, A represents a car-truck of common type having two parallel longitudinal bars *a a'* on edge and suspended from the journal-box.

40 B represents the rail.

The brake-shoe is supported by the bars *a a'* through the intervention of a bracket C. This bracket has a horizontal plate *c* extending beneath the two bars, there being a toe *c'*

45 at the outer edge of the plate, which extends up onto the outer side of the bar *a*. The bracket has also the vertical plate *c'*, which lies in contact with the inner side of the bar *a'*. The bracket is held to the bars by the 50 screw-bolts D passing through a plate E on the top of the bars and screwing into the plate *c*. On the bracket C are a pair of bosses *c* *c'*,

which receive studs from the brake-shoe, as hereinafter described.

The brake-shoe is designated F. It consists of the back plate *f*, having a series of integrally-projecting pole-pieces *f'* and the integral end pieces *f''*. The pole-pieces, of which four pairs are shown, are wound to become horseshoe-magnets, and there may be 60 any desired number of these pairs. The winding G is preferably about alternate poles only, as this is cheaper than winding all of them and gives the magnet the required strength. The course of the winding and its magnetic 65 effect is indicated in the diagram Fig. 6, where each of the poles around which the winding takes is a north pole, (designated N,) and the other poles are south poles, (S.) After the winding G is in place, side plates *f* 70 are secured to the back piece, preferably by screws. A suitable filling, as cement, H is packed in about the wound and unwound poles, and a bottom plate *f*, made of brass, so as not to close the magnetic circuit, and 75 having holes for the projecting poles closes in the filling and winding, being held in suitable manner, as by the bolts *f*. A multi- 80 polar magnet is thus provided, which has projecting ends adapted to form a very efficient 85 braking-surface.

Extending upward from the brake-shoe are a pair of studs J, which preferably screw into the back *f* and into two of the pole-pieces *f'*. These studs extend through openings *c* in the 85 bosses *c* of the bracket C, and above the bosses are surrounded by helical protrusile springs K, which are compressed and adjust- 90 ed by the nuts L L'. The brake-shoe is thus elastically supported above the rail and nor- 95 mally out of contact with it, but may move into contact therewith whenever current passes around the coils G. The terminals *g* of these coils may be connected by the controller either with the trolley-current or with the car-motors as generators.

If the brake is in engagement when the car is going around a curve, the center of the openings *c* in the bosses would not be over the center of the tread of the rail, and for this 100 reason I make these openings flaring laterally from top to bottom, so that the shoe may swing outward or inward, as the case may be, to remain in contact with the tread of the rail.

The openings c^4 , however, are of the same width throughout in a longitudinal direction, so that there is no unnecessary play between the shoe and the car. This clearly appears in Fig. 7.

Having described my invention, I claim—

1. A brake-shoe F in the shape of a long rectangular box consisting of the straight back plate f , the ends f^2 and the straight sides f^5 extending downward from the back plate, the straight flat base-plate f^3 of non-magnetic material engaging with said sides and ends and having a plurality of openings through it, a series of pole-pieces carried by said back plate in a straight row and extending through the openings in said base-plate whereby they may be caused to simultaneously engage a straight rail, and electric windings with the box, substantially as described.
2. A brake-shoe having a back plate f , the integral pole projections f' lying in a straight line, the end plates f^2 , the winding G around some of said poles, side plates f^5 , the base-plate f^3 of non-magnetic material inclosing the coils and having holes through which the pole-pieces project, and a pair of studs J extending from the back plate f , substantially as described.
3. A rigid bracket C consisting of a plate c' adapted to extend beneath a truck-beam, a plate c^2 adapted to lie along a vertical side of said truck-beam, and bosses c^3 above the plate c^2 and joining both plates, combined with a magnetic brake-shoe carrying studs extending from it through openings in said bosses, substantially as described.
4. The combination, with a pair of parallel bars of a truck, of a bracket C, bolts D lying between the bars and securing the bracket

thereto, a pair of bosses carried by the bracket, 40 vertical holes through the bosses, studs going through the holes and a brake-shoe carried by the studs, substantially as described.

5. The combination, with a railway-car, of a bracket carried thereby and having openings therein, a brake-shoe having a pair of studs lying in said openings, means tending to retain the brake-shoe elevated, there being play between the walls of said openings and the studs in a lateral direction but not in a 45 longitudinal direction, substantially as described.

6. The combination with a car of a bracket carried thereby having vertical holes extending through it which holes flare laterally but 50 not longitudinally, a brake-shoe having studs extending through said holes, and springs surrounding the studs and tending to hold the brake-shoe out of engagement with the rail, substantially as described.

7. The combination with a railway-truck, of a bracket adapted to be secured thereto, said bracket carrying bosses c^3 , vertical holes through said bosses which holes flare downward laterally but not longitudinally, a brake- 65 shoe having studs extending through said holes and engaging with the front and rear walls thereof, springs surrounding said studs and bearing on the bosses, and means carried by the studs for holding the springs compressed, substantially as described.

In testimony whereof I hereunto affix my signature in the presence of two witnesses.

EDWARD M. BARNES.
